UNITED STATES PATENT OFFICE.

EDWIN HART, OF WATERBURY, CONNECTICUT, ASSIGNOR TO THE NEW ENGLAND WATCH CO., OF WATERBURY, CONNECTICUT, A CORPORATION.

DESIGN FOR A WATCH-DIAL.

40,393.

Specification for Design.

Patented Dec. 14, 1909.

Application filed October 11, 1909. Serial No. 522,206. Term of patent 14 years.

To all whom it may concern:

Be it known that I, EDWIN HART, a citizen of the United States, residing at Waterbury, in the county of New Haven and State of Connecticut, have invented a new, original, and ornamental Design for a Watch-Dial; and I do hereby declare the accompanying drawing to be a full, clear, and exact illustration of the same, and which said drawing constitutes part of this specification, and

represents a face view of a watch-dial embodying my design.

Claim.

The ornamental design for a watch dial, as shown.

EDWIN HART.
